COMBINATION FLUSH AND STORAGE TANK
FOR TOILETS OR THE LIKE

Horace Duckenfield, San Francisco, Calif.

Application February 3, 1945, Serial No. 576,034

4 Claims. (Cl. 4—68)

1

The present invention relates to improvements in combination flush and storage tanks for toilets or the like, and its principal object is to provide, in connection with a flush tank of the character described, a pocket or auxiliary chamber adapted for storing various objects, and particularly intended for accommodating the toilet brush commonly used for cleaning the toilet bowl.

For this purpose it is proposed to provide a special compartment or pocket at one side of the flush tank without increasing the size of the latter, and to arrange the special pocket in such a manner that it will be kept dry and that drippings from the brush will automatically join the main circuit of the flush tank.

It is further proposed to provide a common cover for the main compartment and the auxiliary compartment, and in one preferred form, to arrange the cover in such a manner that it may be moved partially to give access to the special pocket, while the main portion of the cover remains supported on the flush tank.

The storing of a toilet bowl brush is a source of inconvenience. It should remain near the toilet, for obvious reasons, and cannot readily be accommodated in the storage or shelf space usually provided in a bath room, principally for sanitary reasons.

If left standing against the wall, it becomes unsightly and detracts from the appearance of a modern bathroom.

It is proposed, therefore, to provide storage space for the brush within the flush tank where the brush will be out of sight, and does not come into contact with any other objects which might become contaminated.

Further objects and advantages of my invention will appear as the specification proceeds, and the novel features of the same will be fully defined in the claims hereto appended.

The preferred form of my invention is illustrated in the accompanying drawing, forming part of this application, in which:

Figure 1 shows a front view of a flush tank, a portion being shown in section;

Figure 2, a front view of a modified form of flush tank having my invention incorporated therein;

Figure 3, a section taken along line 3—3 of Figure 2;

Figure 4, a side view of the flush tank, looking at it from the left side; and

Figure 5, a side view of the flush tank, looking at it from the right side.

While I have shown only the preferred form

2

of my invention, it should be understood that various changes or modifications may be made within the scope of the claims hereto attached, without departing from the spirit of the invention.

Referring to the drawing in detail, the flush tank 1 illustrated in Figure 1, may be of substantially conventional form, comprising a rear wall 2, a bottom 3, side walls 4 and 5, a front wall 6, and a cover 7.

10 In accordance with my invention, the tank is divided into two compartments 8 and 9 by means of a vertical partition 10, which runs parallel to the side wall and is positioned fairly close to one of the side walls 5, so as to make the compartment 15 relatively small as compared with compartment 8, which latter may be referred to as the main compartment and is adapted to accommodate the flushing apparatus normally provided in a flush tank.

20 The flushing apparatus may be of any suitable, conventional type, and is not illustrated in detail in the drawing. It is operated by means of a handle 11 and the water is discharged through a conduit 12 extending downwardly from the main compartment.

25 The conduit 12 is controlled by means of a valve 13, forming part of the flushing apparatus, and may be of any suitable conventional construction.

The partition 10 extends to the full depth of 30 the tank, from front to rear and substantially to the height of the walls of the tank at least above the normal water level in the main chamber.

The pocket or auxiliary compartment 9 is thus 35 completely protected from the water in the main compartment, and is kept dry except for possible drippings from the toilet bowl brush to be stored therein.

The pocket preferably should be confined to a size sufficient to accomplish its purpose, namely 40 that of storing the toilet bowl brush, and should not substantially decrease the capacity of the main chamber. Any slight difference in capacity might be made up or compensated for by raising the water level in the main compartment.

45 The bottom of the compartment 9 is provided with a drain hole 14 connecting with a drain pipe 15 leading into the main flushing conduit 12 below the level of the flush tank.

Thus, any drippings from the brush stored in 50 the pocket 9 will automatically find their way into the main conduit 12.

The cover 7, shown in Figure 1, is of conventional type, and has to be lifted off by a vertical lift in order to give access to the two compartments of the flush tank.

Since access to the pocket storing the toilet bowl brush is desired more often than access to the main compartment, and since the cover usually is of considerable weight, and inconvenient to handle, I provide a cover 7', shown as a modified form in Figures 2 to 5, inclusive, which is slideable on the flush tank, and which may be moved sidewise for giving access to the pocket 9, without requiring its weight to be lifted.

This cover 7' is formed with a bottom ledge 16 slideable within the tank, so as to clear the partition 10, and with an outer flange 17 running along the front and the left side of the flush tank. The outer flange is omitted on the right side, as illustrated in Figure 5.

This construction allows the entire cover to be moved sidewise, that is to the left, without any lifting effort. It may be moved sufficiently far to give access to the pocket 9, while its main weight still rests on the upper edge of the tank.

My construction of the tank cover greatly facilitates insertion and removal of the brush into and out of the pocket or auxiliary compartment 9.

The operation of my invention will be readily understood from the foregoing description:

If the conventional form of cover shown in Figure 1 is used, a lifting effort is necessary, at least at the right side of the cover, to clear the pocket.

Where the form of Figure 2 is used, it is merely necessary to slide the cover to the left for opening the pocket, and to the right for closing it.

Any drippings adhering to the brush may readily find their way into the main conduit 12.

Thus my invention relieves the bathroom of the unsightly appearance of the toilet brush and provides a storage space which is immediately available, easy of access, removed from all other storage space, sanitary, self-draining and self-ventilating, since each flushing operation draws on the storage chamber from above and from below, and causes a certain amount of agitation in its air space.

I claim:

1. A flush tank for a toilet or the like having an upright partition to provide a main chamber for holding flushing apparatus and an auxiliary chamber for storing objects and having a common cover for both chambers, the partition being constructed for establishing communication between the two chambers above the normal water level in the main chamber to subject the auxiliary chamber to suction when the water in the main chamber recedes during flushing operations.

5 2. A flush tank for a toilet or the like having an upright partition to provide a main chamber for holding flushing apparatus and an auxiliary chamber for storing objects and having a common cover for both chambers, the partition being constructed for establishing communication between the two chambers above the normal water level in the main chamber to subject the auxiliary chamber to suction when the water in the main chamber recedes during flushing operations and the cover and the tank having cooperative guide means whereby the cover may be slid sidewise to uncover the auxiliary chamber while maintaining its balance over the main chamber.

10 3. A flush tank for a toilet or the like having an upright partition to provide a main chamber for holding flushing apparatus and an auxiliary chamber for storing objects and having a common cover for both chambers, the partition being constructed for establishing communication between the two chambers above the normal water level in the main chamber to subject the auxiliary chamber to suction when the water in the main chamber recedes during flushing operations, and the auxiliary chamber having a drain outlet connecting into the main chamber flushing outlet.

15 4. A flush tank for a toilet or the like having an upright partition to provide a main chamber for holding flushing apparatus and an auxiliary chamber for storing objects, a common cover for both chambers, and a drain outlet for the auxiliary chamber connecting into the main chamber flushing outlet, the partition being constructed for establishing communication between the two chambers above the normal water level in the main chamber to subject the auxiliary chamber to suction when the water in the main chamber recedes during flushing operations, and the cover and the tank having cooperative guide means whereby the cover may be slid sidewise to uncover the auxiliary chamber while maintaining its balance over the main chamber.

20 45 HORACE DUCKENFIELD.
